BOAT PROPELLING DEVICE

Gordon E. Daniels, Nashville, Tenn.

Application June 23, 1952, Serial No. 295,004

4 Claims. (Cl. 115—29)

1

This invention relates to manually operable propelling devices for small boats, and has particular reference to devices of this nature which may be readily mounted on, and demounted from, small boats.

Although manually operable boat propelling devices have heretofore been proposed, those of which I am aware embody bearings for rotatably supporting propelling elements, i. e., oars or paddles, such bearings being more or less permanently attached to the boat, thereby rendering it difficult to mount and demount the propelling device as a whole. Further, such bearings, due to the inconvenience of lubricating the same, are subject to wear and noise. Also, the friction developed tends to materially add to the load imposed on the operator in actuating the device.

It therefore becomes a principal object of the present invention to provide a manually operable propelling device which may be readily mounted on or demounted from an existing small boat.

Another object is to reduce to a minimum the frictional load developed by a boat propelling device of this character.

Another object is to eliminate bearings for pivotally supporting a paddling device for small boats.

A further object is to provide a manually operable paddling device for small boats wherein the paddles are retracted out of the water when manual force is removed.

A still further object is to provide a steerable, foot-operated, boat propelling device which is simple and economical to manufacture.

The manner in which the above and other objects of the invention are accomplished will be readily understood on reference to the following specification when read in conjunction with the accompanying drawings, wherein;

Fig. 1 is a plan view of a small boat having mounted thereon a propelling device embodying the present invention.

Fig. 2 is a sectional view taken substantially along the line 2—2 of Fig. 1, and

Fig. 3 is a sectional view taken substantially along the line 3—3 of Fig. 2 but illustrating one of the paddles projected downwardly to better disclose the details thereof.

Referring to the drawings, the propelling device, generally indicated at 10, is mounted for pivotal movement on the sides of a small boat 11 of conventional construction. In order to eliminate bearings and their inherent friction tendencies and yet provide for a pivotal rocking

2

movement of the device, the latter is mounted to roll on the gunwales 12 of the boat.

The device comprises a pair of hollow shafts 13 and 14, bent at 90° to their outer ends to form depending arms 15. In order to maintain the shafts in coaxial alignment at all times, a third shaft 16 is extended a substantial distance at either end thereof into both hollow shafts and is rotatable therein. This arrangement maintains the shafts 13 and 14 in alignment at all times but permits relative rocking movement therebetween.

A collar 17 of fibre or similar material is attached to each of the shafts 13 and 14 and forms a sleeve which is intended to support the respective shaft in rolling contact with the corresponding gunwales 12, or other similar longitudinally extending support member (not shown) attached to the side of the boat.

A paddle 20 is attached to each depending arm 15 in such a manner as to permit feathering of the paddle during a return stroke of the device, while causing the paddle to exert a propelling force against the water during the forward or propelling stroke. For this purpose, the paddle is provided with eye members 21 and 22 in which is rotatably mounted a short rod 23 suitably secured midway between its ends to the outer end of the arm 15. Two light torsion springs 24 and 25 are mounted on the rod 23 on either side of the arm 15. The springs extend between the arm and the paddle to normally urge the latter counterclockwise, as viewed in Fig. 2, to cause a bumper 26 of rubber or the like thereon to abut the arm 15.

For the purpose of independently actuating the paddle 20, a pedal 27 is connected to each of the shafts 13 and 14, enabling operation thereof by the operator's feet. Each pedal is suspended from a bracket arm 28 integral with the respective hollow shaft by a pair of chains 29, the upper ends of which are attached to the outer ends of the arms 28 by bolt 30.

Means are provided to insure rolling action of the shafts 13 and 14 during actuation thereof, and to normally hold the paddle 20 in the position shown by the full lines in Fig. 2 above the water so as not to impede in any way the forward movement of the boat when coasting or otherwise moving under the influence of forces other than those developed by the paddles. For this purpose, two cables 32 and 33 are provided for each of the shafts 13 and 14. Cable 32 is attached to the upper surface of the sleeve 17 by a bolt 34 at one end and extends aft to a

relatively heavy tension spring 35 at the other end. As shown in Fig. 1, the opposite end of the spring is removably attached by a suitable clip 36 to a convenient part of the boat, such as a seat 37.

The second cable 33 is attached at its rear end to the undersurface of each sleeve 19 by a bolt 38 and at its forward end to a suitable anchor or bolt 39, preferably attached to the outside of the boat.

It will be noted in Fig. 2 that the cables 32 and 33 act to retain the respective shafts 13 and 14 in rolling contact with the gunwales 12 during actuation thereof by the operator's feet during a forward stroke, or by the springs 35 during the return stroke. Also, each spring 35 is effective to normally maintain the respective paddle in the retracted position shown in Fig. 2 wherein it is located above the water. During this return stroke of the paddle under the action of the spring 35, the paddle will rock about rod 23 against the action of springs 24 and 25 in a feathering motion until it clears the water.

In order to steer the boat in different directions, one or the other of the paddles may be actuated independently of the other, in which case the aligned shafts 13, 14 and 15 may temporarily roll to a position at an angle to a line perpendicular to the longitudinal axis of the boat. However, upon releasing both pedals to the action of springs 35, the shafts will again take up their proper positions as shown in Fig. 1.

The cables 33, in view of their location directly adjacent the side of the boat, as seen in Figs. 1 and 3, yieldably maintain the shafts 13, 14 and 15 in proper lateral location relative to the boat.

From the above it will be noted that the device can be readily attached to an existing small boat regardless of the width thereof, since the shafts 13 and 14 may be spread apart different amounts to cause the sleeves 17 to properly fit on the boat gunwales 12 or other supporting members, the shaft 16 permitting an appreciable change in the spacing of the shafts.

Having thus described the invention, what I desire to secure by United States Letters Patent is:

1. A propelling device for a boat comprising the combination of a pair of shafts, bearing means interconnecting said shafts for maintaining said shafts in coaxial alignment and for permitting relative rotation of said shafts, means for maintaining said shafts in rolling engagement with the upper surfaces of respective ones of the sides of said boat, a depending arm integral with the outer end of each of said shafts, a paddle carried by each of said arms, and means

for independently and manually rocking said shafts whereby to cause said paddle to propel said boat.

2. A propelling device for a boat comprising the combination of a shaft assembly adapted to roll on spaced longitudinally extending members on said boat, depending arms integral with said shaft assembly adjacent opposite ends thereof, paddles carried by said arms, a cable attachable to said boat forward of said shaft assembly and wrapped in one direction about said assembly, a second cable attachable to said boat aft of said shaft assembly and wrapped in the opposite direction about said shaft assembly whereby to cause said shaft assembly to roll along said longitudinal members upon rocking of said shaft assembly, and means for manually rocking said shaft assembly whereby to cause said paddle to propel said boat.

3. A propelling device according to claim 2 comprising spring means for retracting said shaft assembly from rocked position.

4. A propelling device for a boat comprising the combination of a pair of shafts adapted to be supported by longitudinally extending members on said boat, bearing means interconnecting said shafts for maintaining said shafts in coaxial alignment and for permitting relative rotation of said shafts, a pair of cables attachable to said boat forward of said shafts, and wrapped in one direction about respective ones of said shafts, a pair of other cables attachable to said boat aft of said shafts and wrapped in the opposite direction about respective ones of said shafts whereby to cause said shafts to roll along said longitudinal members upon rocking of said shaft assembly, a depending arm integral with the outer end of each of said shafts, a paddle carried by each of said arms, and means for independently and manually rocking said shafts whereby to cause said paddle to propel said boat.
